(57) **CLAIM**

The ornamental design for a bottle, as shown and described.

DESCRIPTION

FIG. 1 is a front perspective view of a first embodiment of a bottle showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is an exploded view thereof; with the exterior bottle being shown separated for ease of illustration;

FIG. 9 is a front perspective view of a second embodiment of a bottle showing our new design; with the difference residing in a portion of the bottle within the exterior cover being disclaimed;

FIG. 10 is a front view thereof;

FIG. 11 is a rear view thereof;

FIG. 12 is a side view thereof;

FIG. 13 is another side view thereof;

FIG. 14 is a top view thereof; and,

FIG. 15 is a bottom view thereof.

The broken line showing of a side of a bottle, bottle cap, and written label are included for the purpose of illustrating only and forms no part of the claimed design.
